FLATIRON SUPPORT

Frida Schürch and Anton Ilg, Zurich, Switzerland

Application November 18, 1936, Serial No. 111,468
In Switzerland November 22, 1935

2 Claims. (Cl. 248—117.3)

When employing supports for flatirons now in common use, a portion of the ironing board or table is either obstructed so that it is impossible to iron on the entire surface thereof, or alternatively to place the support for the flatiron on a chair adjacent the table. In the latter instance, it becomes necessary for the user of the iron to move about a good deal and to frequently elevate the flatiron from its position on the chair to the surface of the table or ironing board, thus greatly increasing the labor attending the ironing operation.

One of the objects of the present invention is to construct a flatiron support which may stand on or be supported from the ironing board, thus obviating the disadvantages of prior constructions referred to above.

The novel flatiron holder is characterized by a base plate provided with an insulated supporting plate in spaced relation to the base plate. The base and insulating plates are inclined with respect to the horizontal when the holder either rests on supporting legs provided for this purpose or when the holder is hung vertically from an ironing board or table. One of the longitudinal sides of the holder is provided with an upright wall and one of the shorter sides with a transverse wall. The side opposite the aforementioned longitudinal side is characterized by an apertured supporting wall, while the side opposite the transverse wall is open to permit the iron to rest on the insulating plate.

Other constructional features will be pointed out hereinafter and attention is now directed to the drawing forming a part hereof and in which is illustrated one form of the invention and in which:

Fig. 1 is a front elevational view of the novel flatiron support.

Fig. 2 is a sectional view taken on line A—B of Fig. 1 and

Fig. 3 is a perspective view of the novel flatiron holder or support constructed according to the instant invention.

Referring to the drawing, it will be seen that the novel flatiron holder is characterized by an insulating plate 1 in spaced relation to a base plate 2 situated therebeneath. By reference to Figs. 2 and 3, it will be seen that the base plate 2 is characterized by upwardly extending walls 3, 4 and 5 structurally integral therewith and constituting extensions thereof, the wall 3 forming one longitudinal side of the base plate, the wall 4 a transverse side and a longitudinal and broad wall 5, to which reference will be made

hereinafter, the other longitudinal side of the novel ironing holder or support. Each of walls 3, 4 and 5 is provided with inwardly projecting lugs 6 stamped out from the single sheet of metal characterizing the base plate 2 and its walls 3, 4 and 5, said lugs serving to hold the flatiron, when positioned on the insulating plate, in spaced relation to the aforementioned walls. By referring to Fig. 3, it will be appreciated that the wall 4 and its lugs 6 being in a lower horizontal plane 10 than the opposite edge of the insulating plate 1, serves to hold the flatiron in place on said insulating base or plate 1. The base plate 2 is provided with a series of apertures 7 which serve to permit the warm air from the flatiron to circulate about the holder being aided by radiation sheet 8 which has its upper portions fixed to a pair of integral supporting legs 9 and 10, the extremities 11 of which pass through the base plate 2 and forming a space 12 therebetween for retaining the plate 1 in spaced relation thereto. It will be noted that the height of the opposite vertical portions of the legs 9 and 10, respectively, vary, that is, the height of the vertical portions of the legs 9 and 10, respectively, adjacent the side wall 4, is less than the height of the vertical portions of the respective legs adjacent that portion of the base plate 2 not provided with a side wall. A screw 13 serves to fasten the insulating plate 1 to the base plate 2.

Referring for the moment to Figs. 1 and 3, it will be noted that the tall supporting broad wall 5 is provided with a series of spaced apertures 14, and in addition to the inwardly projecting lug 6 on one face of the plate 5, said plate is provided with a series of projections 15 on its opposite side face adjacent the top edge thereof.

An angle iron or a bracket 18 is adapted to be secured to the edge of an ironing board or table, said bracket being provided with a sheet 40 of insulating material 19 on the outer face thereof, and with a pair of spaced buttons or knobs 20. The wall 5 has a pair of openings 21 adjacent the top edge thereof through which the knobs or buttons 20 are adapted to be inserted for detachably supporting the holder on said angle bracket 18. By reason of the projections 15, an insulating space 16 is provided between the bracket 18 and the inner face of the wall 5 of the iron holder.

The manner in which the iron holder may be used is as follows:

When it is desired to support the iron holder from a table, it will be hung from the fixed angle iron or bracket 18 by means of the buttons or knobs 20. It will also be apparent that the hold-

er may be detached from the angle iron or bracket 18 which is permanently fixed to an ironing table or board 22. It will also be obvious that the flatiron may be supported on the insulating plate 1 in a position in which it will not readily be dislodged for the reason that this plate is inclined to the horizontal so that the flatiron is held by gravity against the side wall 4. If desired, the flatiron holder may be supported on its legs 9 and 10, the holder being placed on the ironing table 22 or a chair or other support.

Due to the insulating features of the invention such as the projections 6, insulating plate 1, radiation plate 8 and insulating board 19, the danger of a conflagration resulting from the use of a hot flatiron with the novel flatiron support is virtually limited. Furthermore, the ironing cloth will not be singed or burned, as has been the practice heretofore, when a flatiron is placed thereon.

Other advantages will be apparent to those skilled in the art to which the invention appertains and it will be understood that various changes and modifications may be made in the constructional details of the invention, and it is desired to cover all such, and to be limited in this respect only as may be necessary by the claims hereto appended.

30 What we claim and desire to secure by Letters Patent is:

1. A flatiron supporter holder comprising a base plate having three of its edges bent upwardly to form a pair of longitudinally extending side walls and a transverse end wall, one of said longitudinally extending walls projecting materially above the surface of the base plate and being provided with a series of apertures, said apertured longitudinal wall having means for detachably securing it to a support and said base plate having legs of uneven height at opposed ends thereof, said transverse end wall being adjacent that portion of the base plate having the shorter legs, whereby a flatiron will be positioned in abutting relationship with respect to said transverse wall when the holder is either hung by said apertured longitudinal wall or rests on its legs.

2. In a flatiron supporter holder having a flat base plate three edges of which are bent upwardly to form a pair of longitudinally extending side walls and a transverse end wall, said base plate being provided with spaced apertures, legs of uneven height having the upper end portions thereof projecting through said apertures, an insulating plate above said base plate, the ends of said legs supporting said insulating plate in spaced relation to said base plate, and means securing said insulating and base plates together.

FRIDA SCHÜRCH.
